UNITED STATES PATENT OFFICE.

THOMAS V. GARLOCK, OF CUSTER, SOUTH DAKOTA.

TABLE FOR CHEESE-CUTTERS.

No. 884,810.

Specification of Letters Patent.

Patented April 14, 1908.

Application filed July 16, 1907. Serial No. 384,085.

To all whom it may concern:

Be it known that I, THOMAS V. GARLOCK, a citizen of the United States, residing at Custer city, in the county of Custer and 5 State of South Dakota, have invented new and useful Improvements in Tables for Cheese-Cutters, of which the following is a specification.

This invention relates to improvements in 10 tables for cheese cutters, particularly to tables of that class having retaining knives or blades to enter the cheese to secure it in position.

The primary object of the invention is to 15 provide a construction whereby the table carrying the cheese may be lifted out of engagement with the blades so that the body of cheese may be shifted on the table to center it for accurate cuts, or removed from the 20 table to allow the latter to be cleaned.

A further object of the invention is to provide simple and efficient means for raising and lowering the table and holding the same in an elevated position.

25 With these and other objects in view, the invention consists of the novel construction, combination and arrangement of parts hereinafter fully described and claimed, reference being had to the accompanying drawings, in 30 which:—

Figure 1 is a top plan view of a table for cheese cutters embodying my invention. Fig. 2 is a vertical transverse section thereof on line 2—2 of Fig. 1. Fig. 3 is a detail 35 view of the cam. Fig. 4 is a view similar to Fig. 2, showing a modification in the means for raising and lowering the table. Fig. 5 is a detail view of a portion of the base, showing the guide slot for the outer end of the lever shown in Fig. 4 and the means for locking the 40 lever to hold the table elevated.

Referring now more particularly to the drawings, the numeral 1 represents a base, comprising, as shown, a horizontal plate provided with a depending supporting flange 2, 45 in lieu of which supporting legs of any preferred construction may be used.

Arranged above the base is a table or platform 3, which may be made of wood, metal 50 or any other suitable material. This table or platform is provided with radially disposed slots 4 for the passage of similarly arranged cheese-holding knives or blades 5 carried by a rotating holder 6 disposed below 55 the table and between the same and platform 1. The holder 6 preferably comprises a plate

of skeleton form having a hub 7, a rim 8 and a series of radially arranged connecting arms 9, the rim being arranged to contact with the base and platform. The blades 5 are fixed 60 in any suitable manner to certain of the radial arms 9 and project upwardly through the slots 4 in the table and preferably have their upper ends tapering to points to readily enter the base of the cheese. The body of 65 cheese rests upon the platform 3 and is held from movement thereon by the knives, as will be readily understood.

Secured to the center of the underside of the table 3 is a plate 10 from which depends 70 a circular stud or post 11 passing through openings 12 and 13 in the base and holder, and extending a sufficient distance below the base to guide and center the table in its movements, and to support the same in an elevated 75 position above the knives 5. When the table is in lowered position, both it and the holder 6, which are connected for simultaneous movement by the knives 5, rotate on the post 11, thus enabling the body of cheese 80 to be turned to any position for the purpose of cutting off a portion or segment thereof.

In order to enable the table to be elevated independently of the holder so that the cheese can be released from the knives to permit it 85 to be adjusted on the table or removed therefrom, suitable means are provided for use in connection with the post 11 to raise and lower the table and hold the same in an elevated position.

90 In the form of raising and lowering means shown in Figs. 1 and 2, the base 1 is provided with a pair of depending parallel ears 14 arranged on opposite sides of the post and forming bearings for the inner end of a shaft 15, 95 said shaft being journaled at its outer end in the flange 2 of the base and provided with a hand wheel 16 by which it may be conveniently turned. Keyed or otherwise fixed to the shaft between the flanges 14 is a cam 17 100 bearing peripherally against the underside of the post 11, whereby upon turning the shaft in one direction or the other, the table may be raised or lowered. The extent of upward movement of the table is sufficient to raise 105 its upper surface above the knives 5, as indicated in dotted lines in Fig. 2, whereby the cheese may be freed from connection with the knives and turned to center it for the purpose of cutting an accurate slice, or removed 110 in order that the upper surface of the table may be cleaned. The table itself may be

conveniently removed when desired for a thorough cleaning in an obvious manner. The highest point of the periphery of the cam is formed with a flattened surface 18 which is 5 adapted to bear squarely against the lower end of the post 11, whereby the shaft may be held from turning and the table held or locked in an elevated position for any desired length of time. The spider 6 is provided 10 with a circumferential flange 6^a engaged by overhanging guide and retaining clips 6^b upon the base. These clips allow the spider to freely turn but by bearing on the flange prevent the spider from being elevated with 15 the table in the event that the knives tend to hang in the cheese when the table is elevated.

In Figs. 4 and 5 I have shown a different means for raising and lowering the table, which may be employed independently of 20 the cam mechanism shown in Figs. 1 and 2 or in conjunction therewith, as desired. The raising and lowering means disclosed in Figs. 4 and 5 embodies a lever 19 centrally fulcrumed on a pin 20 carried by ears 21 depending from the base. The inner end of this lever is arranged to bear upon the lower end of the post 11, while the outer end thereof extends to the exterior through a slot 22 formed in the flange 2, thus enabling the 25 lever to swing vertically to raise and lower the table in any obvious manner. Beyond the flange the power end of the lever is formed with a finger piece 23 to permit of its convenient adjustment, and, as shown, the slot 30 22 is formed at its base with a lateral offset 24 provided with a locking shoulder 25. When the finger piece of the lever 23 is depressed the lever will be swung on its fulcrum to raise its inner arm, thus communicating 35 upward motion to the table, and when thus adjusted it will be understood that by shifting the power end of the lever laterally, the portion thereof passing through the slot may be moved into the offset 24 underneath the 40 shoulder 25 which latter will hold the power end of the lever against upward or return movement and thus maintain the table in an elevated position. The lever may be released in an obvious manner when it is desired 45 to lower the table.

It will thus be seen that the invention provides a simple construction of table of the character described, by which the platform may be raised out of contact with the holding knives to permit the table to be turned 55 independently of the knives for the adjustment of the cheese to a centered position to secure an accurate cut, or for the release and ready removal of the cheese in order that the 60 table may be conveniently cleaned.

Having thus described the invention, what is claimed as new, is:—

1. A device of the character described comprising a base, a table mounted to rotate 65 upon the base and provided with slots, a

holder comprising a plate disposed directly between the table and base and provided with cheese holding blades extending upwardly through said slots, said holder being formed with a peripheral rim having a depending portion resting upon the base and provided with an outwardly extending flange, guiding and retaining clips comprising strips fixed at one end to the base and having their free ends bent upwardly over said flange, and means for raising and lowering the table. 75

2. A device of the character described comprising a base having a central opening therein, a table arranged to rotate upon the base and provided with slots, a holder comprising a plate disposed directly between the base and table, said plate being formed with a central opening and a rim having upwardly and downwardly extending surfaces supporting the table and bearing against the base, the downwardly extending portion of the rim being formed with an outwardly extending flange, retaining and guiding clips comprising strips fixed at one end to the base and having their free ends bent upwardly over such flange, cheese holding blades carried by the plate and extending upwardly through the slots in the table, a post carried by the table and projecting downwardly through openings in the holder and base, and means upon the under side of the base to engage the post for raising and lowering the table. 80 85 90

3. A device of the character described comprising a base, a table disposed above the same, a holder arranged between the table and base, a post or stud secured to the table and extending downwardly loosely through the holder and base, retaining knives upon the holder projecting upwardly through slots in the table, and a rotary cam carried by the base and adapted to coöperate with the post to elevate the table. 10

4. A device of the character described, comprising a base having a central opening therein, a rotary table arranged above the base and provided with slots, a rotary holder arranged directly between the base and table, said holder comprising a spider having a central hub registering with the opening in the base, a series of radial arms, and a peripheral rim formed with a depending portion resting on the base and provided with an outwardly extending flange, holding blades carried by the arms and projecting upwardly through the slots in the table, clips comprising strips fixed at one end to the base and having their free ends bent over said flange to retain the holder in guided connection with the base, a post connected with the table and passing downward through the opening in the base and the hub of the holder, and means upon the base and coöoperating with said post for raising and lowering the table. 11 12 13

5. A device of the class described com- 14

prising a base, a rotary table arranged above the base, a rotary holder arranged between the base and table, said holder being provided with retaining blades extending upwardly through slots in the table, a post extending downwardly from the table and journaled in the base and holder, and a rotary cam supported by the base and acting upon the post to raise and lower the table, 10 said cam having means to secure it from rotation and hold the post in an elevated position.

6. A device of the class described comprising a base, a rotary table arranged above the base and provided with slots, a rotary holder arranged between the base and table and provided with retaining blades projecting upwardly through said slots, a post extending downwardly from the table and journaled in the base and holder, and cam mechanism supported upon the base and operative to engage the post for raising and lowering the table.

7. A device of the class described comprising a base, a rotary table arranged above the base and provided with slots, a rotary holder arranged between the base and table and having retaining blades projecting upwardly through said slots, a post depending

from the table and journaled in the base and holder, a shaft journaled on the base, and a cam carried by said shaft, said cam being provided at the highest point of its acting surface with a flattened portion to hold the table in an elevated position.

8. A device of the class described, comprising a base having a central opening therein, a table provided with radial slots, a holder comprising a plate arranged directly between the base and table and having a central opening registering with the opening in the base and provided with cheese holding knives extending upwardly through the slots in the table, engaging means on the base and periphery of the plate holding the latter in guided connection with the base, a post upon the table extending downwardly through said central openings in the base and holder, and means mounted upon the base and operating with the post whereby the table 50 may be raised and lowered to retract and project the blades.

In testimony whereof, I affix my signature in presence of two witnesses.
